ELASTIC BALL VALVE.

1,403,263.

Specification of Letters Patent. Patented Jan. 10, 1922.

Application filed November 14, 1919. Serial No. 338,031.

To all whom it may concern:

Be it known that we, PHILIP MUELLER and ANTON C. SCHUERMANN, citizens of the United States, residing at Decatur, in the 5 county of Macon and State of Illinois, have invented new and useful Improvements in Elastic Ball Valves, of which the following is a specification.

This invention relates to faucets or cocks 10 and has particular reference to the elastic valve members used therein.

Some of the objects of our invention are to so improve the construction of the elastic ball or valve that it will retain its shape for 15 a longer time than balls now generally used, it being provided with means whereby the strain upon the elastic portion of the ball is partly relieved when the valve is closed; the elastic ball is better enabled to resist deformation, and cutting or crushing of the ball 20 when the same is brought against the seat is prevented; and generally the life of the ball is materially increased, and it is particularly efficient in cocks where hot water is 25 used.

The above and other objects of our invention are obtained by the structure set forth in detail in the following specification and illustrated in the accompanying drawings, where- 30 in—

Figure 1 is a longitudinal view through a basin cock showing our elastic ball applied thereto.

Figure 2 is a sectional view taken on line 35 2—2, Figure 1.

Figure 3 is also a sectional view taken on line 3—3, Figure 1.

Referring to the drawings, wherein like numerals represent like parts in the several 40 views, 10 designates a basin cock which may be of any suitable or well-known construction, the same being illustrated as having an eccentric stem 11, which is adapted to receive on its upper end a suitable operating 45 handle (not shown) and having on its lower end an eccentric or crank-portion 12, to which is attached a valve stem 13 by means of a strap portion 14, as is usual. The stem 11 is held in place in the cock body by a cap 50 15 screw-threaded upon the neck portion of the cock, and about the stem 11 are suitable packing rings 16 which form a fluid-tight joint about the same. The shank or inlet end of the cock has a curved valve seat 17 against 55 which our improved elastic ball is adapted to

seat, and the inlet end of the cock is provided with screw-threads for the reception of a tail-piece 18, the tail-piece having on its rear end a suitable screw-threaded shank portion by means of which the cock is connected to 60 the usual supply or service pipe. The cock, above described, is of the usual or well-known type, and is herein shown by way of illustration only.

The rear end of the valve stem 13 which 65 extends rearwardly into the tail-piece is of reduced diameter, and the stem is provided with radially extending wings or guides 19, the tips of which are adapted to engage the inner wall of the reduced portion 20 70 of the faucet shank, whereby the valve is guided and maintained in axial alignment with the tail-piece 18. About the reduced end of the valve stem 13 and adapted for relative longitudinal movement thereon is 75 a sleeve 21 which may be of any suitable construction, but, in the present instance, it is shown, by way of illustration, as consisting of two portions having different diameters, the portion having the larger diameter 80 being designated by the numeral 22, and that of less diameter by the numeral 23. The portion 22 of greater diameter has an internal bore or recess 24 which receives a coil spring 25 adapted to encircle the rear 85 end of the valve stem 13 and abutting at its inner end against the shoulder 26 at the inner end of the bore 24 the said spring 25 tends to maintain the sleeve and stem always in telescoped or contracted relation, but yielding so as to permit the sleeve to slide outwardly on the stem when the elastic valve 90 member is brought to its seat. The spring is retained in the recess by a disk or washer 27 suitably apertured to encircle the end of the 95 valve stem, and the disk is maintained in place by means of a pin 28 passing through a transverse hole or opening adjacent the end of the valve stem. The reduced portion 23 of the sleeve is suitably screw-threaded to receive the internal screw-threads of a brass collar 29 which is substantially of the same diameter as the bore of the reducer portion 20 of the shank of the faucet, so that it may be moved into the reduced portion 20. The 100 collar 29 serves to retain an elastic member or ball 30 upon the sleeve 21, and, in the present instance, this ball or elastic member consists of a shell having substantially the same external diameter throughout its 110

length. A portion of the shell has an internal diameter corresponding to the outer diameter of the larger portion 22 of the sleeve 21, and another portion of the shell has a 5 reduced internal diameter corresponding to the diameter of the small portion 23 of the sleeve 21, so that the elastic ball or shell may be slipped over the sleeve, the shoulder 31 obtaining between the portions of different 10 diameters of the elastic ball or shell engaging against the oppositely disposed shoulder of the sleeve 21. The outer end of the enlarged portion 22 of the sleeve 21 is externally screw-threaded for the reception of 15 a cap 32, which cap encloses the rear end of the valve stem and the spring 25, and it has an annular groove or recess 33 which, when the cap is in place, receives the rear end of the elastic shell 30, as will be seen in the 20 drawings. The elastic ball may or may not be provided with a protecting shell as desired, but, in the present instance, we have illustrated the end of the shell rearward of 25 the valve seat end thereof as being enclosed or encircled by a protecting ring 34 having its rear end crimped inwardly as at 35, to prevent the ring from working or moving forwardly toward the valve-seat end of the elastic ball. The encircling ring or shell 34 30 prevents, to a certain degree, radial spreading or squashing of the elastic or flexible ball when the same is brought against its valve seat.

The manner in which our improved elastic 35 ball is assembled will be readily understood from Figure 1, it being noted that before applying the sleeve 21 to the valve stem, the elastic ball 30 is slipped over the forward end of the sleeve until the shoulder 31 of the 40 elastic shell engages the oppositely disposed shoulder of the sleeve 21, and then the retaining collar 29 is screw-threaded upon the portion 23 of the sleeve to retain the elastic ball upon the sleeve. The sleeve is then inserted over the reduced end of the valve stem 13, the spring 25 placed in the recess 24 and about the reduced end of the stem, and the 45 spring is then locked in place by means of the washer 27 and the pin 28. The sleeve is maintained against the shoulder provided 50 upon the valve stem at the front end of the reduced portion thereof due to the tension of spring 25. The cap 32 is then screw-threaded over the rear end of the sleeve 21 55 to close the recess 24, and the cap is moved a sufficient distance upon the end of the sleeve to force the rear end of the elastic ball into the annular groove 33. Thereafter the protecting ring 34 is slipped about the rear end 60 of the elastic or flexible ball.

When the eccentric stem 11 is turned to open the valve, the crank portion 12 moves the valve stem 13 rearwardly and the shoulder on the valve stem forces the sleeve 21 rearwardly, and thereby withdraws the

elastic ball or valve member 30 from the valve seat 17. When the eccentric stem 11 is turned to close the valve, the elastic ball is brought into engagement with the valve seat to close off the water. It will be noted 70 that should the elastic ball not be provided with some yielding or resilient means, the ball would, of necessity, be compelled to take up the entire strain to which it is subjected when brought into engagement with the 75 valve seat, and upon repeated operation, the ball would likely be crushed or give away under the strain to which it is submitted. After the valve or ball 30 is brought to its 80 seat and upon continued turning movement of the eccentric stem 11 in a direction tending to further close the valve, the spring 25 is placed under compression and the valve stem 13 moves relatively to the sleeve 21, and thus the spring relieves the ball from 85 some of the pressure to which it would otherwise be rigidly subjected. Thus the ball would not be crushed or its seating surface cut, although the handle of the eccentric be turned to full cut-off position, and at the 90 same time should any parts of the valve or the ball 30 itself become worn, the spring would take up any resultant play and the ball would be yieldingly retained against the seat, and leakage past the valve would be 95 prevented when the cock is closed.

It will be noted that the elastic valve body 30, throughout its length encircles the sleeve 21 and the ball is maintained against longitudinal movement relative to the sleeve by 100 oppositely disposed abutments, both of which are carried by the sleeve, these abutments being, in the present instance, the shoulder 31 of the sleeve and the collar 29. With this arrangement the sleeve is interposed between the stem 13 and the ball 30 so 105 that there is no contact therebetween, and thus wear upon the ball and the tendency for the ball to bind about the sleeve and prevent free movement of the latter under influence 110 of spring 25, are guarded against.

It is, of course, obvious that our invention is susceptible of various modifications and changes, but we do not wish to limit ourselves to the particular embodiment herein illustrated and described unless so limited by the 115 following claims:

What we claim is:

1. In combination, a valve stem; a sleeve 120 slidably mounted on said stem; means normally to hold said sleeve and stem in telescoped relation; a stop to limit the telescoping movement of said sleeve and stem; and an elastic valve body mounted on and movable with said sleeve, said valve body being 125 out of contact with said stem whereby the valve body may be yieldingly drawn to its seat.

2. In combination, a valve stem, a sleeve 130 slidably mounted on said stem, an elastic

- valve body mounted on and movable with said sleeve entirely out of contact with said stem, means carried by the sleeve to prevent relative movement between the sleeve and valve body, a stop for limiting the movement of the sleeve on the stem in one direction, and means for urging said sleeve against said movement limiting stop. 5
3. In combination, a valve stem, a sleeve 10 slidably mounted on said stem, an elastic valve body mounted on and movable with said sleeve and terminating short of the forward end thereof, a stop on the stem forming an abutment against which the forward end of the sleeve engages to limit forward movement of the sleeve, and means for urging said sleeve towards said stop. 15
4. In combination, a valve stem, a sleeve 20 slidably carried thereby, a stop on the stem for limiting movement of said sleeve in one direction, an elastic valve body carried by said sleeve, and terminating short of the end of said sleeve to permit the sleeve to engage said stop, and a spring about the stem for urging said sleeve toward said stop. 25
5. In combination, a valve stem, a sleeve 30 slidably mounted on said stem, an elastic valve body mounted on and movable with said sleeve, a flange carried by the sleeve and against which the valve seat end of the valve body engages, and yieldable means carried by the stem and urging said sleeve and its valve body thereon forwardly on said stem. 35
6. In combination, a valve stem, a sleeve 40 slidably mounted on said stem, an elastic valve body mounted on and movable with said sleeve, a flange carried by the sleeve and against which the valve seat end of the valve body engages, a shell about said elastic valve body, and yieldable means carried by the stem and urging said sleeve forwardly on said stem. 45
7. In combination, a valve stem, a sleeve 45 slidably mounted on the stem and having a recess at one end, a spring in said recess en-
- circling the end of said stem, means for preventing the withdrawal of the stem from said spring, and an elastic valve body mounted on said sleeve. 50
8. In combination, a valve stem having a shoulder intermediate its ends, a sleeve 55 slidably mounted upon the stem and engaging against said shoulder, said sleeve being of two portions of different external diameters and the larger portion having an enlarged bore or recess, a spring in the recess encircling said stem, means for preventing the withdrawal of the stem from the spring, and an elastic valve body about the sleeve 60 the internal periphery of which is of different diameters corresponding to the external diameters of the sleeve. 65
9. In combination, a valve stem, a sleeve 70 slidably mounted upon said valve stem and having a flange at one end and a longitudinal recess or bore at the other end, a spring in said recess about the stem and engaging said sleeve, means for preventing the withdrawal of the stem from the spring, an elastic valve body about the sleeve abutting at one end against said flange, and means at the recessed end of the sleeve for retaining said valve body against withdrawal from the sleeve. 75
10. In combination, a valve stem having a shoulder intermediate its ends, a sleeve 80 slidably mounted upon the stem and adapted to engage against said shoulder, said sleeve having an internal recess, a spring in said 85 recess encircling said stem and engaging said sleeve, means for preventing the withdrawal of the stem from said spring, a cylindrical elastic valve body upon said sleeve, a collar upon said sleeve and engaging the seating end of said valve body, a cap screw-threaded over the recessed end of said sleeve, and a shell about said valve body. 90

In testimony whereof we have hereunto set our hands.

PHILIP MUELLER.
ANTON C. SCHUERMANN.
